UNITED STATES PATENT OFFICE.

JOSEPH S. WEEKS, OF LOS ANGELES, CALIFORNIA.

COMBINED ROCKER ARMCHAIR AND DESK.

Application filed October 4, 1926. Serial No. 139,393.

The invention forming the subject matter of this application is a chair adapted for use either as a rocker or castored arm-chair provided with means designed, when desired, to serve as a desk or table suitable for writers, invalids or other persons.

The objects of the invention will become apparent as the detailed description thereof proceeds.

10 In the drawings:—

Figure 1 is a perspective view of my invention with the desk-table structure shown in operative position;

15 Figure 2 is a fragmentary detail elevation of the mechanism for converting the chair from a rocker chair to a castored roller arm-chair;

20 Figure 3 is an elevational detail showing the desk-table members in folded position; and

Figure 4 is a fragmentary sectional view of a toggle locking joint forming part of the invention.

25 As illustrated in the drawings, my invention comprises a chair having legs 1, 2, 3, and 4 suitably framed with the usual rails and braces to form a seat 5, back 6 and arm rails 7. The lower ends of the legs 1 and 4 have a rocker 8 fixed thereto, and a similar 30 rocker 9 is likewise secured to the lower ends of the legs 2 and 3.

Outwardly of the rockers 8 and 9, each leg is shaped to form an offset 10 and a recess 11 to receive a chair supporting member 12. 35 A pair of these members 12 are shown in the drawing as hinged to the offsets 10 of the legs 2 and 3 to swing about the hinges 13, and are of such length that when fully seated in their recesses 11 their ends extend 40 below the rocker 9 to support it out of contact with the floor.

In order to swing the members 12 about their hinges 13 into and out of their recesses 11, a toggle linkage has the ends 14 and 15 of its links 16 and 17, respectively, connected by hinges 18 to the opposed inner sides of the members 12 of the legs 2 and 3. These links are pivoted to each other by a common rule joint 19, which is provided 50 with a clamping pivot nut 20 adapted to be operated to secure the toggle and the supporting members 12 in operative or inoperative position as desired. A ball castor 21, of any suitable or desired construction, is secured to the end of each member 12 to enable the chair to be rolled wherever desired,

in the usual way, when the supporting members 12 are in chair supporting position.

While the description so far has been limited to the showing of the chair supports and toggle members as connected to the legs 2 and 3 only, it is to be understood, of course, that the supporting members 12 on the legs 1 and 4 are similarly hinged to the offsets 10 and are operated by a toggle linkage similar to the linkage just described.

The desk-table parts of my invention comprise a board 22 connected to one of the arms 7, near its front end, by a parliamentary hinge 23 to project laterally of the arm 7 a sufficient distance to accommodate the board extension 24 when the said parts are in folded position (see Figure 3).

Where the distance between the desk supporting arms 7 is greater than the height 75 of these arms above the rockers 8 and 9 or the ends of the members 12, when the latter are in chair-supporting position, it is necessary to make the board 22 shorter than this height, so as to permit this board to 80 swing clear of the floor when it is moved to folded position, and to hinge to the free end of this board an extension 26 of sufficient length to extend to the other arm 7 and serve as a support for the board 22. This 85 extension 26 must, of course, be folded up against the board 22 as indicated in Figure 3, and may be secured in this folded position by any suitable latch 27.

The extension 24 is connected to the board 90 22 by pairs of double action hinges to adapt said extension to hang down and behind the board 22 when folded, or to be raised into operative position, when desired. An extensible bracket, having cooperative telescoping parts 29 and 30, has its opposite ends pivotally connected to the leg 2 and the under side of the extension 24, a clamping thumb screw 31 being provided to lock the parts 29 and 30 in any desired relative 95 positions and to hold the extension 24 in any convenient position.

The board 22 may be curved or shaped as found convenient or desirable to accommodate the body of the person using the chair. 100

The operation and uses of the invention will be obvious without further description.

Having thus described my invention, what I claim as new and desire to secure by Letters Patent is:—

110 1. A chair having rockers fixed to the lower ends of the legs thereof, said legs having

- offsets at their lower ends extending outwardly and laterally of said rockers to form support-receiving recesses, supports pivoted to said offsets to swing into and out of said recesses and of lengths sufficient to raise the rockers out of floor contact when swung into said recesses, and means connecting front and rear supports in pairs to lock them in rocker raising positions.
- 10 2. A chair having rockers fixed to the lower ends of the legs thereof, said legs having offsets extending laterally from said ends to form recesses, supports hinged to

said offsets to swing into or out of said recesses and of sufficient length to raise the chair with its rockers out of contact with a floor when swung into the recesses, and toggle linkages connecting the front and rear supports in pairs to lock them in rocker raising positions in said recesses.

15 3. The chair as set forth in claim 2 in combination with means for locking said linkages in any desired position.

20 In testimony whereof I have signed my name to this specification.

JOSEPH S. WEEKS.
